UNITED STATES PATENT OFFICE.

JOHN STUART SMITH, OF McHENRY, KENTUCKY.

LUBRICATING CAR-WHEEL.

No. 829,038.

Specification of Letters Patent.

Patented Aug. 21, 1906.

Application filed October 6, 1905. Serial No. 281,578.

To all whom it may concern:

Be it known that I, JOHN STUART SMITH, a citizen of the United States, residing at McHenry, in the county of Ohio and State of Kentucky, have invented a new and useful Lubricating Car-Wheel; and I do hereby declare the following to be a full, clear, and exact description of the invention, such as will enable others skilled in the art to which it applies to make and use the same.

This invention relates to railroad-cars, and more particularly to the wheel, having novel lubricating means for continually supplying the oil to the journal of the wheel.

The object of the invention is to provide a device of this character which is simple in construction and which can be manufactured at a very slight cost and at the same time be sold to the trade comparatively cheap.

Another object of the invention is to provide a chambered portion in the body portion of the wheel in which the oil is adapted to be contained, so that by the centrifugal motion of the wheel the body part of the oil will have a tendency to adhere to the outer portion of the chamber and will only allow a small quantity to spray therefrom in the rotation of the wheel.

A further object of the invention is to provide a cylindrical-shaped cap which is inserted over the end of the axle for the purpose of holding the wheel in correct position in relation to said axle, said cap being provided with oil-ducts which are slightly inclined to allow the oil to find its way to the chambered portion.

A still further object of the invention is to provide means for automatically closing the end of the cap after oiling.

This invention comprises, further, objects and combinations of elements, which will be hereinafter more fully described, and shown in the accompanying drawings, and the novel features thereof will be pointed out by the appended claims.

To obtain a full and correct understanding of the details of construction and combinations of features, elements, and advantages, reference is to be had to the hereinafter-set-forth description, in connection with the accompanying drawings, wherein—

Figure 1 is a longitudinal vertical section through a car-wheel, showing the journal portion of the axle with the invention applied thereto. Fig. 2 is a cross-sectional view on

line 2 2 of Fig. 1. Fig. 3 is a longitudinal vertical section through a car-wheel on line 3 3 of Fig. 2, and Fig. 4 is a view showing a modification of the invention.

Making renewed reference to the accompanying drawings, wherein similar reference characters indicate the corresponding parts in the several illustrations by figures, I designates the body of a car-wheel, having a chambered portion 2, which is adapted, if desired, to hold packing to prevent the waste of the lubricating material. The body of the wheel is provided with a cylindrical bore 3, adapted to receive the journal portion 5 of the axle 6. The rear of the journal portion is provided with an abutment-hub 7 to prevent the wheel from moving inward, as shown clearly in the accompanying drawings. The outer face of the body portion of the wheel is provided with a cylindrical inclined bore 8, which is of larger diameter than the bore 3 of the wheel, and said cylindrical inclined bore 8 is an extension of the chambered portion 2 and also connects with said chambered portion, so as to allow the oil to find its way from the inclined oil-ducts 9 of the cylindrical-shaped cap 10, the end of which fits a cylindrical recess 11, which is provided in the outer portion of the bore 8, as shown clearly in the accompanying drawings. Said cylindrical cap 10 is provided with inclined oil-ducts 9, as before stated, which are circular in cross-section, as shown clearly in Fig. 2 of the accompanying drawings. Said cap is also provided with similar ducts 12 intermediate the ducts 9, which are of the form of longitudinal recesses. The said ducts 12 open into and connect, as at 13, with the cylindrical bore 14 of the cap 10. In this way the lubricating material also finds its way to the journal portion, as at 15, which portion fits within the bore of said cap, as clearly shown in Figs. 1 and 2 of the accompanying drawings.

The journal portion of the axle which fits the cap 10 is provided with a V-shaped annular recess 16, which receives the conical-shaped ends 17 of the set-screws 18, which are inserted through the wall of the cap 10, as shown clearly in Fig. 1 of the accompanying drawings. This V-shaped annular recess not only provides means for receiving the conical-shaped ends 17 of the set-screws for preventing displacement of the cap and wheel, but serves as a reservoir in which a certain amount of oil lodges for the purpose of lubri-

cating the conical-shaped ends of the set-screws, so as to allow the said conical-shaped ends of the set-screws to travel smoothly and freely within said V-shaped annular recess, 5 and, furthermore, part of the oil which lodges in said recess finds its way to the bore of the cap for lubricating the said bore. The outer face of the cap 10 is provided with an opening 19 and also a threaded cylindrical recess 20, 10 which is adapted to receive a suitable packing 21 to prevent the oil from being wasted through said opening 19. Said opening 19 receives a plug 22, the ends of which are conical-shaped in opposite directions, as at 23 and 24. Said plug is provided with a suitable check-valve 25, whereby as the oil-can is inserted within the end of the plug said check-valve will be pushed open against the tension of a suitable spring 26, which will allow 15 the oil to flow through the conical-shaped bore of the plug 22, after which the oil will find its way to the chambered oil portion 27, from which it will flow through the ducts 9 and then into the chambered portion 2 of the body portion of the wheel, as shown clearly in Fig. 1 of the accompanying drawings. The said spring 26 is mounted upon the stem 25' of the valve 25 and also interposed between the valve-disk and across bar 26', which 20 spans the conical-shaped bore of the plug 22.

The conical-shaped ends, as at 23 and 24, of the plug 22 are provided for the purpose of preventing the plug from moving in either direction. The conical-shaped end 23 of the 25 plug 22 is placed within the opening 19 of the outer portion of the cap, after which suitable packing 21 is placed around said plug, over which a suitable packing-nut 28 is placed, which is provided with screw-threads to engage 30 the threads of the cylindrical recess 20 of the cap 10, which will prevent the plug from moving outward.

From the foregoing description it will be plainly observed that a very efficient journal-lubricating device for wheels is provided which is simple in construction and which may be manufactured at a very slight cost and sold to the trade comparatively cheap.

Having described the invention, what is 45 claimed as new, useful, and novel is—

1. A lubricating device comprising a cap having an oil-chamber, oil-ducks and a central opening, a hollow plug fitting in said opening, which opening is beveled to prevent inner movement of the plug, means to prevent 50 the outer movement of the plug and

means for automatically closing the opening in the plug.

2. A lubricating device comprising a cap having an oil-chamber, oil-ducks and a central opening, a hollow plug fitting in said opening, said opening having means to prevent inner movement of the plug, means to prevent the outer movement of the plug and a check-valve for the plug. 60

3. A lubricating device comprising a cap having an oil-chamber and inclined oil-ducks therein, a plug for the end of the cap, provided with means to prevent the inner movement thereof and a packing-nut to prevent the outer movement. 65

4. A lubricating device comprising a cap having an oil-chamber and inclined oil-ducks therein, there being an opening in said cap, a plug to be received by said opening, means to prevent outer movement thereof, there being inclined walls in said opening to prevent the inner movement. 70

5. In a lubricating device for wheels and axles, a cylindrical cap carried by the end of the axle and having an oil-chamber and inclined oil-ducks, a check-valve-controlled plug for the end of said cap, said axle having an annular V-shaped groove, thumb-screws carried by the cap and having V-shaped ends 80 to fit in said annular groove to prevent outward displacement of the cap there being means to prevent the inner movement of the plug. 85

6. A lubricating device for wheels and axles, comprising a wheel, an axle, said axle having a cylindrical hub portion to limit the inward movement of the wheel, said wheel having a chambered portion, a cylindrical inclined bore communicating with said chambered portion, and a cylindrical recess adjacent to said bore, a cap fitted over the end of the axle and having one end engaging said recess, which cap is provided with an oil-chamber, and inclined oil-ducks, a plug fitted in the outer end of said cap and having its ends conical-shaped in opposite directions, a check-valve carried by said plug, a packing-gland for said plug, and means to prevent outward movement of the plug. 95

In testimony whereof I have hereto affixed my signature in the presence of two witnesses.

JOHN STUART SMITH.
